UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 6, 1922. Serial No. 605,167.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

10 This invention relates to feeler mechanisms for looms.

In that type of feeler mechanisms generally known as "side slipping" or "side swipe," it is now the general practice to provide the feeler with teeth for engaging the filling on a detecting beat, and when the filling is substantially exhausted, the feeler is given a side slipping movement 15 along the filling carrier or bobbin in the direction of its length, and during such movement the usual teeth now provided on feelers of this type are liable to scratch or mar the surface of the filling carrier or bobbin and, in a measure, also to retard the side slipping movement of the feeler.

One of the objects of the present invention is to provide a side slipping feeler with a filling engaging tip which while effective to 20 hold the feeler from movement longitudinally of the shuttle when a working supply of filling is present on a detecting beat, will not injuriously affect the filling carrier or bobbin or retard the side slipping movement of the feeler.

In accordance with the present invention, the side slipping feeler is provided with a tip, the feeler holding or toothed portion of which normally engages the filling transversely of the longitudinal axis of the filling carrier or bobbin, and when the filling is substantially exhausted on a detecting beat and the feeler partakes of its side slipping movement, turns to present the feeler holding or toothed portion of the tip into substantially parallel relation with the longitudinal axis of the filling carrier or bobbin, the effect being that as the side slipping feeler moves in a direction longitudinally 25 of the shuttle, the holding or toothed portion of the tip offers no impediment to such movement and does not injuriously scratch or mar the surfaces of the filling carrier or bobbin.

55 The improvements constituting the present

invention are illustrated in the accompanying drawings, in which:

Fig. 1 is a perspective view of sufficient portions of the loom and the feeler mechanism, looking from the rear, to show the 60 construction and operation of the invention;

Fig. 2 is an enlarged detail perspective view of the tip portion of the feeler and the connection between the feeler tip;

Fig. 3 is an enlarged detail showing the 65 engagement of the feeler tip with the filling on the filling carrier or bobbin when a working supply is present on a detecting beat;

Fig. 4 is a cross-section showing the feeler tip engaged with the filling; and

Fig. 5 is a view similar to that of Fig. 3 but with the filling substantially exhausted on a detecting beat and the feeler slipping in a direction longitudinally of the filling carrier or bobbin.

70 Except in the respects to be hereinafter particularized, the feeler mechanism as shown is similar to that illustrated and described in Letters Patent of the United States, No. 1,309,226, dated July 8, 1919; 75 and while the advantages of the present invention are more particularly manifested in connection with the type of side slipping feeler of the above mentioned patent, the invention may be employed advantageously 80 in other forms of side slipping feeler mechanisms.

It has not been deemed necessary herein to show and describe the replenishing mechanism which is set in operation to effect 90 replenishment of filling when the feeler partakes of its side slipping movement, because the details of such mechanism form no substantial part of the present invention and are now well understood.

95 The feeler mechanism is mounted at the front of the loom and, as shown, is adjustably secured by the bolt 1 and slot 2 to a bracket 3 connected to an extension 4 of the shipper stand.

The feeler stand 5 through which the bolt 1 extends is shown as having a bracket 6 in which is swivelled a front bearing 7, and the rear portion of the feeler stand 5 has bearings 8 for a slide 9 which is movable 100 transversely of the feeler stand. The slide 9 has an extension 10 to which is connected the transmitter 11 through which replenishment of filling is initiated.

105 The rear bearings 8 have a slotted por-

110

tion 12 and the feeler 13 passes through a smaller slot 14 in the slide 9 and into or through the bearing 7. A cap piece 15 is secured to the rear bearings 8 by screws 16 and serves to hold the slide 9 in its sliding position. The feeler 13 is supported by a bridge 17 and between the bridge and the front bearing 7 is a spring 18 which normally acts to hold the feeler in its rearward or feeling position. All the parts thus far described may be substantially as disclosed in the patent here before mentioned.

The lay 19 has the usual shuttle box 20, the front wall of which is provided with an opening 21 for the entrance of the feeler, and similarly the shuttle 22 which supports the filling carrier or bobbin 23 in the usual manner has its front wall provided with an opening 24 which coincides with the opening 21 when the shuttle is in the box at the feeler side of the loom, the construction being such that on a detecting beat the feeler 13 may enter the openings 21 and 24 and feel for the filling.

The feeler 13 has its end portion provided with a feeler tip of novel construction and, as shown, the rear end portion 25 of the feeler is turned or formed to present a tip support, the rear end face 26 of which is preferably plain.

The feeler tip 27 is preferably connected to the feeler as at 28, which constitutes a horizontal axis for the feeler. The pivotal support 28 of the feeler tip may be provided with a head 29 for conveniently holding the feeler tip to the feeler.

The feeler tip, as shown in Fig. 4, carries a feeler holding or toothed portion 30 for engagement with the filling on a detecting beat. In the present instance the feeler holding or toothed portion 30 of the feeler tip is constituted by a single tooth which, on a detecting beat, sinks into the filling, as indicated in Fig. 4, when a working supply is present in the shuttle.

The pivotal support 28 for the feeler tip connects the feeler tip eccentrically with the feeler, as shown, and the feeler tip itself by reason of the eccentric mounting and the preponderance of weight of the feeler tip at one side of the pivotal spring 28, normally occupies the position indicated in Figs. 2, 3 and 4, so that when a working supply of filling is present in the shuttle on a detecting beat, the feeler holding or toothed portion of the feeler tip engages the filling transversely of the longitudinal axis of the filling carrier or bobbin, Figs. 3 and 4, and sinks into the filling to an appreciable extent. While the present embodiment of the invention shows the feeler tip provided with a single tooth for engaging the filling, it is evident that more than one tooth may be employed if desired.

Feeler mechanisms of the side slipping type are given their side slipping movement when the filling is substantially exhausted on a detecting beat either by means of the forward pressure upon the feeler or by some mechanical means, and in accordance with the present invention, the eccentrically pivoted and supported feeler tip by engagement with the filling on a detecting beat prevents such side slipping movement of the feeler when a working supply of filling is present in the shuttle, and is itself also held from turning movement relative to the feeler at such times by sinking into the filling.

When, however, the filling is substantially exhausted on a detecting beat and the holding or toothed portion of the feeler tip no longer restrains side slipping movement of the feeler, the feeler will partake of its side slipping movement and owing to the eccentric connection of the feeler tip with the feeler, the feeler tip will be caused to turn upon its pivotal mounting to present the holding or toothed portion of the feeler in substantial parallelism with the longitudinal axis of the filling carrier or bobbin, as indicated in Fig. 5, the effect being that the holding or toothed portion of the feeler tip will slip or slide along the surfaces of the filling carrier or bobbin without injurious effect thereto.

Thus when a working supply of filling is present in the shuttle on a detecting beat, the toothed portion of the feeler tip will engage the filling in the normal position of the tip, which is determined by the weight of the tip in the present instance, and the tip itself will be held from swinging relatively to the feeler by the toothed portion of the tip sinking into the filling. When, however, the filling has become substantially exhausted on a detecting beat, as indicated in Fig. 5, and the feeler partakes of its side slipping movement, the feeler tip will be caused to swing in its pivotal connection with the feeler to present the toothed portion of the feeler tip in lengthwise relation to the surfaces of the filling carrier or bobbin.

What is claimed is:

1. In a feeler mechanism for looms, the combination of a feeler mounted for movement towards and from the front of the loom and in a direction longitudinally of the shuttle, a feeler tip pivotally mounted on the feeler for swinging movement in a substantially vertical plane and held from such swinging movement by engagement with the filling until substantial exhaustion thereof on a detecting beat and thereupon caused to swing in such vertical plane by movement of the feeler in a direction longitudinally of the shuttle.

2. In a feeler mechanism for looms, the

- combination of a feeler mounted for movement in a direction longitudinally of the shuttle, a feeler tip mounted on the feeler for movement relative thereto about a substantially horizontal axis and held from such relative movement by engagement with the filling on a detecting beat until the filling is substantially exhausted and then caused to move about such axis as the feeler moves in a direction longitudinally of the shuttle. 3. In a feeler mechanism for looms, the combination of a feeler mounted for movement in a direction longitudinally of the shuttle, a feeler tip mounted on the feeler for movement about a substantially horizontal axis and having a filling engaging portion which sinks into the filling on a detecting beat and holds the feeler tip from such movement until the filling is substantially exhausted and thereupon frees the feeler tip to movement about its horizontal axis as the feeler is moved longitudinally of the shuttle. 4. In a feeler mechanism for looms, the combination of a feeler mounted for movement in a direction longitudinally of the shuttle, a feeler tip having a portion which normally engages the filling in a direction substantially transverse to the longitudinal axis of the filling carrier on a detecting beat until the filling is substantially exhausted and movable into a position substantially parallel to the axis of the filling carrier by movement of the feeler in a direction longitudinally of the shuttle. 5. In a feeler mechanism for looms, the combination of a feeler mounted to enter the shuttle on a detecting beat in a direction inclined to the longitudinal axis of the shuttle and for side slipping movement, a feeler tip having a tooth normally supported to engage the filling substantially transverse to the longitudinal axis of the filling carrier until the filling is substantially exhausted on a detecting beat and movable to a position substantially parallel to the longitudinal axis of the filling carrier as the feeler is given its side-slip movement. 6. A feeler mechanism for looms having a side slipping feeler with a tip which is pivotally connected to the feeler for free swinging movement on an axis substantially at right angles to the longitudinal axis of the shuttle. 7. A feeler mechanism for looms having a side-slipping feeler with a tip for engaging the filling mounted on the feeler to swing in a substantially vertical plane when the feeler side slips. 8. A side-slipping feeler having a toothed tip eccentrically mounted on the feeler to freely swing in a vertical plane. 9. A side-slipping feeler having a toothed tip eccentrically pivoted on the feeler to freely swing on a horizontal axis. 10. A side-slipping feeler having a tip mounted eccentrically to swing about axis substantially at right angles to the longitudinal axis of the shuttle and weighted to hold it in a normal position. 11. In a feeler mechanism for looms, the combination of a side-slipping feeler, a feeler tip having a toothed portion which normally extends transversely of the longitudinal axis of the filling carrier and engages the filling on a detecting beat, and a connection between the feeler and feeler tip which permits the toothed portion of the tip to move into lengthwise relation to the surface of the filling carrier when the side-slipping feeler moves longitudinally of the shuttle. 12. A side slipping feeler having its rear end flattened into a plain surface and a feeler tip eccentrically pivoted to the feeler to swing over the flattened plain surface of the feeler end.

In testimony whereof, I have signed my name to this specification.

ISAAC SNOW.
